UNITED STATES PATENT OFFICE.

CARL G. SCHULLER, OF BRECKSVILLE, OHIO.

ROTARY CUTTING TOOL.

Application filed June 28, 1926. Serial No. 118,940.

This invention relates to cutting tools for soft, semi-soft or solid material, particularly for sculpturing wax patterns for dental restorations. In making plate restorations the sides of the finished plate next to the tongue, cheeks and lips should conform as nearly as possible to the original contour of the mouth. The usual method employed includes the step of placing wax over the pattern and gouging out concavities therein, following the shape of the patient's mouth, as nearly as possible by reference to the original plaster cast. Suitable wax is of such a consistency that it cannot be plasticly moulded and hence it has hitherto been necessary to perform this sculpturing with a narrow blade. This was of course, a very tedious operation. It has been attempted to use tools similar to a dental burr, driven in the usual manner, for working such wax, but hitherto no rotary tool has been successfully used for the reason that the severed material almost immediately clogs the blades and renders the tool useless. This is mainly due to the fact that the cutting blades of such tools have not been made with enough clearance for chips and for the further reason that the blades are of such shape that the severed material is not properly ejected clear of the main body of material.

The primary object of my invention is to provide a rotary tool for sculpturing material such as wax, which tool will not clog. A further object is to provide a tool head suitable for the above purpose which may be readily made from a single piece of sheet metal.

Further objects include the provision of a rotatable tool which will eject the severed material backwardly along the axis of rotation. Another object is to provide a tool which will eject the severed material when used for lateral as well as for endwise cutting, whereby the pattern may be more evenly and accurately followed.

Further advantages will become apparent from the following description of my invention which relates to the accompanying drawing, showing the preferred form. The essential characteristics will be summarized in the claims.

In the drawing Fig. 1 is a side elevation of my tool, a portion of the shank being broken away. Fig. 2 is a plan view of the

tool head. Fig. 3 is a cross section, taken along the line 3-3 on Fig. 2 showing the transverse shape of the blades. Fig. 4 is a radial cross section taken along the line 4-4 on Fig. 2. Fig. 5 is a perspective view 60 of the tool mounted for operation. Fig. 6 shows an alternate method of attaching the tool head to the shank.

In carrying out my invention I preferably employ a single piece of sheet metal having a central body portion 1 and blades 2. The body portion as shown in Figs. 1 and 4 is cupped as at 3 and from the brim of the cup the blades extend upwardly and outwardly. The blades are shown as 70 twisted substantially along a non-radial line, this line being indicated in Fig. 2 at L. As a result of such twisting, that portion of a given blade which lies toward the axis of rotation is a gradual upward curve, while 75 beyond the line L the blade curves downwardly, the shape being shown most clearly in Fig. 1. The downwardly extending portion of the blades is indicated at 2^a. It 80 will be apparent that when the tool is rotated, the chips will be held against being thrown directly outwardly since they will be for the most part constrained to move along the blades in the concavity or channel 85 leading backwardly from the cutting edges (the bottom of such channel being substantially along the line L) until they are thrown clear of the tool in the general direction of the shaft.

The preferred contour of the blades is 90 shown in Fig. 2. It will be noted that each blade is inclined forwardly toward the direction of rotation, the front edge of each blade extending substantially in a straight 95 line at 2^b and then abruptly curving as at 2^c, the edge adjacent such abrupt curve extending backwardly at the rear of the blade in a gradual curve as at 2^d. The front edge, the abrupt curve, and a portion of the gradual rearward curve may be sharpened 100 as for example by grinding as at 5. As shown in Fig. 1 these sharpened edges rise from a plane normal to the shaft to about the central portion of the abrupt curve and then recede (in a direction parallel to the stem) to provide a lateral cutting edge. The purpose of this is to enable the operator to cut laterally straight into the wax, or by turning the head in its own 105 plane, to cut laterally in a curve if desired.

In Fig. 4 I have shown a convenient method of attaching the head to a driving shank indicated at 8. This consists in providing a generous shoulder 9 against which the central body portion rests, the end of the shank being simply riveted over beyond the opening 10 in the body portion as at 11. If desired the shank may be formed as shown in Fig. 6, namely with a slight shoulder 12 and reduced end 13, in which case the central body portion of the head would be formed into a tube 14 fitting over the cylinder 13 for lateral support. The forward end of the shank may be riveted over as before or a small quantity of solder may be attached to both the end of the shank and to the sheet metal of the head as at 11^a.

Fig. 5 shows the tool in operation and the relative size thereof to the human hand. It is to be understood, however that different sized tools may be used as required, a larger tool serving best for roughing out the work and a smaller one being used for forming narrow concavities to more accurately copy the pattern. A smaller tool, for example, is best adapted to shaping the wax leading up close to and between the artificial teeth.

By the use of my tool and with a small amount of practice the operator is enabled to copy the natural undulations of the gum adjacent the teeth, almost line for line, with surprising speed as compared with the old method. The tool head is shown in Fig. 5 as making an endwise cut in the coating of wax designated M, in which use the sharpened edges 2^b and 2^c are active. To cut a narrower groove the same tool may be turned so that substantially the only active cutting edge is that designated 2^a. In this latter use it will be seen that the chips will not clog the tool, since the severed chips will be constrained to follow along the bottoms of the concavities of the blades, namely substantially along the line L and hence will be for the most part thrown backwardly along the stem.

While I have described in detail the exact contour of the blades shown, I do not wish to be limited thereto since I believe that I am the first to make a tool for this purpose that may be conveniently formed from sheet metal. The contour of the blades while following my general scheme of construction may moreover be varied according to the consistency of the material to be cut since harder material will call for a less steep pitch than soft wax.

Having thus described my invention, I claim:

1. A rotary tool for the purpose specified comprising a shaft and a head having a central body portion and blades extending outwardly therefrom, each being rounded at its end and contacting with a perimetrical line at substantially one point only, each of the

blades being twisted along a non-radial line to provide a concavity extending substantially entirely across the blade in such manner as to guide and deflect chips inwardly from such perimetrical line and backwardly in the general direction of the shaft. 70

2. A sheet metal tool for gouging or carving soft solid material, comprising a head portion and a shank, said head portion consisting of a single piece of sheet metal having a central body portion and blades extending forwardly out of the plane of the body portion and then outwardly, each of said blades being rounded at its outer end and twisted to provide cutting edges at the 80 end thereof in different transverse planes. 75

3. A tool comprising a driving shaft and a head provided with separated blades, each blade being sharpened at its outwardly disposed edges and each blade being twisted whereby the sharpened edges are disposed in different transverse planes to enable the tool to cut laterally of the shaft when rotated and to forcibly eject the severed material away from the material to be operated upon. 90 85

4. A rotary sheet metal tool for gouging or carving soft material, such as wax, comprising a central portion having blades extending outwardly therefrom and twisted along a non-radial line, said blades being 95 rounded at their ends and having sharpened edges extending along the rounded ends, whereby the tool may gouge the material along different edges while being turned through an angle of 90 or more degrees 100 about an axis lying along its plane of rotation. 100

5. A tool for cutting and forming soft material comprising a single piece of sheet metal having a central body portion, adapted to be secured to a drive shaft, and outwardly extending blades, said blades being twisted to provide a cutting edge the forward cutting edges of each blade being inclined forwardly from its root with reference to a radial line through the center of rotation, the end contour of the blade adjacent such cutting edge being abruptly curved, and the heel of the blade leading backward to the body portion in a more gradual curve. 110 105

6. A rotary sculpturing tool comprising a single piece of sheet metal having twisted blades inclined toward the direction of rotation and being concave, the concavities extending substantially along non-radial lines and entirely across the respective blades. 120 115

7. A tool for dental sculpturing in soft material comprising a single piece of metal having a central cup-shaped body portion, adapted to be secured to a drive shaft, and upwardly and outwardly extending blades, contiguous with the brim of the cup, said blades being separate from each other at such brim and warped to provide lateral cutting edges and inclined chip ejecting sur- 130 125

faces, whereby the chips may be thrown forcibly backward clear of the work when the tool is rotated.

8. A rotary tool comprising a sheet metal head having separated twisted blades extending therefrom and sharpened at their edges, the head being centrally apertured to receive a stem, a stem for supporting the head having its end formed on two diameters to provide a shoulder, the body of the

tool being substantially flush with the extreme end surface of the stem, and means for securing the stem and body portion together consisting of material such as solder extending in overlapping relation to the end 15 of the stem and said head.

In testimony whereof, I hereunto affix my signature.

CARL G. SCHULLER.
